UNITED STATES PATENT OFFICE.

JOHN C. GEBHART, OF ST. LOUIS, MISSOURI, ASSIGNOR, BY MESNE ASSIGNMENTS, TO ECONOMETER COMPANY, OF ST. LOUIS, MISSOURI, A CORPORATION OF MISSOURI.

MACHINE FOR MEASURING TEXTILE FABRIC.

1,259,389.

Specification of Letters Patent. Patented Mar. 12, 1918.

Application filed August 13, 1917. Serial No. 185,963.

To all whom it may concern:

Be it known that I, JOHN C. GEBHART, a citizen of the United States, residing at St. Louis and State of Missouri, have invented 5 new and useful Improvements in Machines for Measuring Textile Fabrics, of which the following is a specification.

This invention relates to an improvement in machines for measuring textile fabric 10 and more particularly to a machine of that type wherein the fabric to be measured is passed between rollers, one of which is employed as a power roller to effect the operation of the measuring instrumentality, 15 and wherein means are provided for separating the rollers to facilitate the introduction or removal of the fabric and for slitting the fabric at the completion of the measuring operation to furnish an indication of the line along which the measured length is to be cut or torn from the rest of the goods.

Certain conditions are encountered in practical use which makes it desirable that 25 the two operations of separating the rollers and slitting the fabric should be independent, notwithstanding that it has been proposed in the prior art to perform the two operations in correlation and by the operation of a common element.

The principal object of the present invention, therefore, is a measuring machine having a conveniently accessible arrangement of devices for the operation of the 35 means for separating the rollers and slitting the fabric wherein either means may be operated independently of the other as required but the operation of either means is effective to prevent the operation of the 40 other thereby insuring that the two means may not be operated simultaneously and that one means may not be operated until the completion of the operation of the other.

With the above object in view the invention generally stated, consists in the provision of a device, operable by either means in its normal operation for positively preventing an operation of the other and arranged to act on both means in preventing 50 their simultaneous operation and also in certain specific features of structure, combination and relation which will be set forth in detail as the description proceeds.

An embodiment of the invention is dis-

closed in the accompanying drawings, 55 wherein:

Figure 1 is a side elevation partly broken away, of a textile fabric measuring machine in which the features of the invention are incorporated.

Fig. 2 is a vertical cross sectional view on the line 2—2 of Fig. 1.

Fig. 3 is a horizontal sectional view on the line 3—3 of Fig. 2, the upper roller being omitted.

Fig. 4 is a detail cross sectional view on the line 4—4 of Fig. 3.

Similar characters of reference designate corresponding parts throughout the several views.

The fabric to be measured is drawn between upper and lower rollers 1 and 2, one of which, in the embodiment disclosed the upper roller 1, is used as a power roller for the operation of the measuring instrumentality.

The invention is not concerned with the particular structure of the measuring instrumentality and, as a matter of convenience, is disclosed as embodied in a machine which, as to its principal parts, is similar in structure, organization and mode of operation to the machine disclosed in my pending application, Serial No. 150,113 and therefore requires only a general description.

The upper roller is utilized to operate a drum 3 which carries a suitable chart, e. g. a chart for indicating measured lengths, total price, or both. The drum 3 is mounted on a shaft 4 which is located above and extends at a right angle to the shaft 5 upon which the roller 1 is mounted. The shaft 5, is connected by suitable gearing to the shaft 4 whose operation is controlled by a clutch having a slideable member 6 in coöperation with a companion member 7. The engagement of the clutch members being established by a spring 8 and their disengagement by a slidably manually operated stem 9. Upon the disengagement of the clutch members the drum 3 is zero set by a spring 10, the return movement of said drum being arrested by the engagement of a lug 11 with which it is provided with a fixed lug 12. The tension of the spring 10 may be regulated by a pivotally adjustable plate 13 having pins 14

to which the outer convolution of the spring is secured, said plate being held in a desired position by a suitable fastening 15.

One of the rollers is mounted in a movable carrier which is operated to space the rollers from one another to facilitate the introduction of the fabric into the machine or its removal therefrom. In the embodiment disclosed the shaft 5 of the roller 1 has fixedly mounted bearings but the bearings 16 for the shaft of the roller 2 are fitted in a frame 17 which is pivoted at one side thereof, as at 18, for movement about a horizontal axis and is pressed upward to hold the roller 2 in operative relation to the roller 1 by a suitable spring 19.

In the embodiment disclosed the frame 17 is lowered to space the roller 2 from the roller 1 by the operation of an arm 20 which at its free end engages a projection 21 on said frame (Figs. 1 and 3); and the frame is held in its lowered position by a spring pressed pivoted latch finger 22 (Fig. 4) co-acting with a projection 23 on said frame. The latch finger 22 is operated to disengage the projection 23 by a manually actuated slidably mounted stem 24 which is pivotally connected to the upper end of said latch finger; and upon the disengagement of the projection 23 by the finger 22 the spring 19 is effective to raise the frame 17 and establish the normal operative relation of the rollers 1 and 2.

Upon the completion of the measuring operation the fabric is slit or otherwise marked to furnish an indication of the line along which the measured length is to be cut or torn from the rest of the goods. In the embodiment disclosed the means for this purpose includes a stationary blade 25 (Fig. 3) and a movable blade 26.

The invention contemplates the lowering of the frame 17 and the operation of the blade 26 in independent operations and includes means for preventing either operation during the practice of the other. The preferred construction in accordance with the invention is as follows.

The arm 20 and the blade 26 are operated by levers 27 and 28, respectively, which are mounted in adjacency at the same side of the machine, the lever 28 being operated to return the blade 26 to its normal position by a spring 28^a. The lever 28 and blade 26 are mounted upon a rock shaft 29 (Fig. 2) which is tubular to provide a bearing for the rock shaft 30 upon which the lever 27 and arm 20 are mounted, the shafts 29 and 30 being disposed transversely to the axes of the rollers 1 and 2. The arm 20 is held against the end of the shaft 29 by a nut 31 on the inner end of the shaft 30 and the blade 26 is pressed laterally to insure its effective co-operation with the blade 25 by a spring 32 surrounding the shaft 29 and confined between

the arm 20 and the hub of the blade 26. Washers or liners 29^a are preferably mounted on the shaft 29 in the space between the hub portion of the knife 26 and the adjacent wall of a casing 42 to be hereafter referred to.

The arm 20 and blade 26 are provided with angular upstanding projections 33 and 34 respectively (Figs. 1 and 3) which are located radially relatively to the pivots of said arm and blade and said projections have beveled inner side faces 35 which mutually converge in a direction (rearward) opposite to that (forward) in which the arm 20 and blade 26 project. The projections 33 and 34 co-operate with a lock finger 36 arranged between them. The finger 36 is pivoted at its rear end for movement in a horizontal plane to a bracket 37 and is held centered between said projections by flat springs 38 engaging opposite sides of its heel portion. At its front end the finger 36 is provided with an engaging head 39 which forms a T with the shank or body of said finger and therefore projects from each side thereof. The head 39 is located very slightly in advance of the projections 33 and 34 when the latter are in their normal positions and in the path of the beveled faces 35 of said projections.

When the arm 20 is operated to lower the frame 17 the projection 33 will be moved forward and in such movement will, with its face 35, engage the head 39 and move the same laterally into a position wherein it projects immediately in front of the projection 34 with which the said head co-operates as a lock to hold the blade 26 against operation at any stage of the operation of the arm 20. In like manner when the blade 26 is operated the projection 34 will move the head 39 into a position wherein it projects immediately in front of the projection 33 with which it similarly co-operates as a lock to hold the arm 20 against operation at any stage of the operation of the blade 26. If the levers 27 and 28 be depressed simultaneously the head 39 will wedge between the faces 35 and prevent any operative movement of either the arm 20 or blade 26.

In the embodiment disclosed and preferred the arm 20 bears upon the projection 21 but its bearing end is free and consequently when the frame 17 is quickly raised by the spring 19, as above described, the arm 20 is thrown upward. Said arm, in order that its upward movement may be suitably limited is provided with a rearwardly projecting lug 20^a (Fig. 1) which when the arm is raised co-operates with a fixed stop 20^b.

It will thus be seen that either the blade 26 or arm 20 may be operated at any period of the operation of the machine, as desired but that said elements cannot be operated

simultaneously and their operation is necessarily independent. In this way conditions which are peculiar to the selling of fabrics by retail are met and overcome. For example a purchaser may order a given length of material and when the length is measured and the cost ascertained may change the order and specify a less or greater length. Such a change can be made without loss to the merchant when the material has not been slit or marked and the capacity of the machine for separating the rollers while the knife is held inoperative is of advantage in this case. On the other hand, a purchaser having in mind some special use for the material may desire it to be slit or marked at regular intervals to indicate contemplated divisions of the material. This can be done by the operation of the blade 26 without impairing the measuring operation and without loosening the grip of the rollers 1 and 2 or removing the material from the machine. Again, with certain kinds of fabric it may be desirable to omit the slitting or marking of the measured length and in such a case the material is measured and removed from the machine without an operation of the blade 26.

The various parts are inclosed in a casing 30 having a slot 41 through which the fabric is inserted or removed from between the rollers 1 and 2. The levers 27 and 28 and other actuating devices are of course, accessible externally of said casing.

The rollers 1 and 2 and their appurtenant elements are preferably supported by a casing 42 arranged within the casing 30 and having a slot 43 to register with the slot 41. The shaft 29 has its bearing in the casing 42 and the hub of the lever 28 preferably has a bearing in the casing 30.

Having fully described my invention, I claim:

1. A machine for measuring textile fabric having a pair of rollers between which the fabric to be measured is drawn, one of the rollers serving as a power roller, a movably mounted carrier for one of the rollers, means for moving the carrier to effect the spacing of the rollers from one another, means for applying to the fabric an indication of the line along which the measured length is to be cut or torn, and means operable by either of said two first named means in the operation thereof for preventing an operation of the other.

2. A machine for measuring textile fabric having a pair of rollers between which the fabric to be measured is drawn, one of the rollers serving as a power roller, a movably mounted carrier for one of the rollers, means for moving the carrier to effect the spacing of the rollers from one another, means for

applying to the fabric an indication of the line along which the measured length is to be cut or torn, a pair of projecting elements, one movable with each means in the operation thereof, and an arm for operation by either of said elements to coöperate with the other as a lock in preventing an operation of the means with which said other element is movable.

3. A machine for measuring textile fabric having a pair of rollers between which the fabric to be measured is drawn, one of the rollers serving as a power roller, a movably mounted carrier for one of the rollers, an arm for moving the carrier to effect the spacing of the rollers, a blade for slitting the fabric to furnish an indication of the line along which the measured length is to be cut or torn, rock shafts upon which the respective arm and blade are mounted, one of said rock shafts being tubular and surrounding the other, levers connected to the respective rock shafts, a pair of companion projections provided respectively on said arm and blade and movable therewith, and an arm for operation by either of said projections to coöperate with the other as a lock in preventing an operation of the arm or blade, as the case may be with which said other projection is associated.

4. A machine for measuring textile fabric having a pair of rollers between which the fabric to be measured is drawn, one of the rollers serving as a power roller, a movably mounted carrier for one of the rollers, an arm for moving the carrier to effect the spacing of the rollers, a blade for slitting the fabric to furnish an indication of the line along which the measured length is to be cut or torn, rock shafts upon which the respective arm and blade are mounted, one of said rock shafts being tubular and surrounding the other, levers connected to the respective rock shafts, a pair of companion projections provided respectively on said arm and blade and movable therewith, said projections having adjacent beveled faces which converge rearwardly, and a pivoted arm normally held centered between said projections and provided with a head for engagement by the beveled faces of said projections whereby it may be operated by either of them to coöperate with the other in preventing an operation of the arm or blade, as the case may be, with which said other projection is associated.

In testimony whereof I have hereunto set my hand in presence of two subscribing witnesses.
